UNITED STATES PATENT OFFICE.

ROBERT McARTHUR, OF BIDDEFORD, MAINE.

FIRE-EXTINGUISHER FOR TEXTILE MACHINERY.

SPECIFICATION forming part of Letters Patent No. 770,817, dated September 27, 1904.

Application filed August 27, 1902. Serial No. 121,157. (No model.)

To all whom it may concern:

Be it known that I, ROBERT McARTHUR, a citizen of the United States, residing at Biddeford, in the county of York and State of Maine, have invented certain new and useful Improvements in Fire-Extinguishers for Textile Machinery; and I do hereby declare the following to be a full, clear, and exact description of the invention, such as will enable others skilled in the art to which it appertains to make and use the same.

The present invention relates to an improved fire-extinguisher for textile machinery.

It is the practice in textile mills to provide the various portions of textile machinery with automatic sprinklers, so that when fire from any cause starts in any machine the sprinkler will be set in operation and the fire extinguished. In feeders, particularly feeders for preparing machines of cotton machinery, the common construction of such machines has involved the use of an open hopper, into which the cotton was placed by the workman, and which feeder automatically operated to carry such cotton in regular and proper quantities to the other machinery, it sometimes happened that a blazing or smouldering fire would start in the open hoppers. If the fire started into a blaze, the cotton, being highly inflammable, would blaze up rapidly and communicate fire to other portions of the room.

I have produced a fire-extinguisher for textile machinery which is adapted to overcome the objections which obtain against prior devices and which embodies certain features of invention hereinafter particularly defined and claimed.

In the accompanying drawings, illustrating the preferred form of my invention, Figure 1 is an end elevation, and Fig. 2 is a sectional elevation, of a cotton-feeder; and Figs. 3 and 4 are respectively an elevation and a plan of a fusible link, hereinafter referred to.

The feeder illustrated in the accompanying drawings (designated by the reference character 1) is the well-known Kitson automatic feeder, into which the cotton from the bale is thrown by the attendant. The cotton is taken up by the spiked apron 2 and carried over to the beater 3, from whence the cotton proceeds,

through the trunk 4, to the other machinery. The bin or hopper 5 of the feeder I have provided with a hood 6, which incloses the top of the feeder. The hood is provided with a lid 7, hinged thereto, which is normally held open by a link 8, secured at one end to the lid and at the other end to some stationary part of the machine. The link 8 is provided with a fusible connection 9, (shown in detail in Figs. 3 and 4,) which consists of two plates 10, soldered together by a solder which melts at a low temperature. I have also provided the hood with an automatic sprinkler 11.

If the cotton in the feeder should take fire, the heat would rise to the top of the casing of the machine, where it would accumulate until sufficient to melt the fusible connection 9 and permit the lid 7 to fall, thereby immediately inclosing the feeder and preventing the spread of fire therefrom. The closing of the lid 7 operates to prevent the access of air to the machine and will, in many cases, be sufficient to extinguish the fire. If, however, the temperature in the feeder continues to rise, the automatic sprinkler 11 will be set in operation and the fire will be extinguished.

I prefer that the fusible link 9 should melt at a lower temperature than will be sufficient to set the sprinkler in operation, so that if the closing of the lid 7 is sufficient to extinguish the fire the inconvenience incident to the operation of the sprinkler may be avoided.

My invention contemplates the use of a casing of any sort for inclosing the cotton or other material operated on by a textile machine, with a closure for the same normally held open by some device which melts or burns or is otherwise rendered inoperative upon the application of heat to permit the inclosing means to inclose the machine, thereby preventing the spread of the fire and tending to extinguish the same by preventing the access of air thereto. It is highly important in this class of machinery that the spread of the fire should be prevented, and I believe I am the first to produce a textile machine having inclosing means operating upon a rise of temperature in the machine to inclose the machine.

Having thus described my invention, I claim as new and desire to secure by Letters Patent—

1. A textile machine, having, in combination, means for inclosing the machine, means normally holding said inclosing means open rendered inoperative by heat to permit the 5 inclosing means to inclose the machine, and an automatic sprinkler, said holding means being made to become inoperative and the sprinkler being made to start upon a rise in temperature in or about the machine, substantially as de-
10 scribed.

2. A textile machine, having, in combination, means for inclosing the machine, means normally holding said inclosing means open rendered inoperative by heat to permit the

inclosing means to inclose the machine, and an 15 automatic sprinkler, said holding means being made to become inoperative at a lower temperature than that which starts the sprinkler so that the machine will be inclosed before the sprinkler is set in operation, substantially as 20 described.

In testimony whereof I affix my signature in presence of two witnesses.

ROBERT McARTHUR.
